UNITED STATES PATENT OFFICE.

CARL E. PUTNAM, OF FAIRPORT, NEW YORK, ASSIGNOR OF ONE-HALF TO FRED A. PUTNAM, OF KEENE, NEW HAMPSHIRE.

HAND-OPERABLE LABELING MACHINE.

Application filed May 22, 1926. Serial No. 111,067.

This invention relates to improvements in labeling machines and the object thereof is to provide a simple and convenient machine which may be carried in the hand and operated to apply adhesive to the under face of the label and to affix the label upon the article to which it is to be applied by bodily movement of the machine.

The usual methods of applying labels to boxes and other articles comprise first the usual hand method which consists in laying the labels face down upon a bench or plate, applying paste to each label with a brush as it is laid down and after a number of labels have been thus pasted, removing the labels individually, placing the same upon the articles by hand and wiping them down with a cloth; second, employing a suitable machine to apply paste to the label and afterwards applying the label to the box or other article by hand and wiping it down with a cloth. Such machines vary from simple hand-operated devices to which the labels are fed by hand, to power driven automatic label feeding machines having a conveyer to carry the pasted labels to the operator, so that the latter may apply them to the boxes or other articles by hand; third, automatic machines in which the labels and packages are fed into the machine and the labels automatically pasted and wrapped upon the boxes or articles.

The present invention comprises a machine which is carried in the hand and is provided with a reservoir for the adhesive and a label support with manually-operable means for advancing the label, applying adhesive thereto and by the bodily movement of the machine affixing the label to the article.

One of the features of the invention comprises an adhesive-applying roller which with a co-operating roller serves to advance the label and apply adhesive thereto and which is actuated by the finger of the operator.

Another feature of the invention relates to means for regulating the amount of adhesive applied to the label.

A further feature of the invention comprises means, preferably in the form of a squeegee roller, operable simultaneously with the rotation of the adhesive-applying roller to apply the label smoothly upon the article to which it is to be affixed.

Other objects and features of the invention will more fully appear from the following description and the accompanying drawings and will be particularly pointed out in the claims.

A preferred embodiment of the invention is illustrated in the accompanying drawings in which Fig. 1 is a side elevation of a portable labeling machine.

Fig. 2 is a plan view of the same;

Fig. 3 is a longitudinal sectional view showing a number of labels carried by the label-supporting means, and a label in the act of being applied to a box, and

Fig. 4 is a detail plan view of the adhesive-applying roller and a stripper for the labels passing over the adhesive-applying roller.

The label pasting machine illustrated in the drawings comprises a chambered base 1 providing a reservoir 2 for adhesive. The front end wall 3 of the base is bevelled to present a label-supporting and guiding surface 4 which desirably extends at an angle to the plane of the bottom of the base 1. A top or cover 5 for the reservoir is secured to the base and a handle member is secured to said cover centrally thereof. The handle member comprises a hand grip 6 which preferably extends in parallelism to the cover 5, the front end of the hand grip 6 being integral with an inclined plate 7 which has at its lower end a boss 8 which is secured by a screw 9 to the cover 5. The other end of the hand grip 6 is formed integral with an inclined tubular support 10 having at its lower end a flange 11 which is screwed to the cover member. The longitudinal chamber 12 of the handle support 10 communicates with a corresponding aperture 13 in the top and provides a conduit through which the reservoir may be filled with adhesive. The upper end of the conduit 12 desirably is provided with a screw-threaded plug 14 to prevent the escape of adhesive.

An adhesive-applying roller 15 is journaled in the side walls of the reservoir adjacent the front end 3 thereof and is partially submerged in the adhesive. A label support, desirably in the form of a plate 16, is adjustably secured to the plate 7 of the handle member and is provided at its lower end with an arcuate surface complementary to the surface of the roller. The label support 16 as illustrated herein is provided with

slots 17 and 18 to receive bolts 19 and 20 which are seated in the plate 7 and secure the label support adjustably thereto. A doctor blade 21 desirably is adjustably clamped between the label support 16 and the plate 7.

Preferably the adhesive-applying roller 15 is provided with a plurality of annular grooves into which strippers 22 project which serve to remove the labels from the adhesive-applying roller and cause it to pass over the inclined guiding surface 4. The doctor blade 21 has projections which are complementary to the grooves of the roller. By reason of this construction the label support 16 may be adjusted in desired proximity to the roller and the doctor blade may be so set as to regulate the thickness of film of adhesive which is applied by the adhesive-applying roller to the under face of the label.

20 A single label or pile of labels which have been so manipulated that their lower ends are successively exposed may be held by the hand of the operator or other suitable means upon the label support so that the lowermost 25 label may be fed to the adhesive-applying roller which is rotated by suitable means to advance the lowermost label and apply adhesive thereto.

In order to ensure a proper feeding of the 30 labels a co-operating presser roll 23 is provided which is journalled in bearings 24 which are slidably mounted in bearing blocks 25 which are secured to the label support 16. Suitable helical springs 26 which are interposed between the bearing blocks 25 and co-operating plates 27 serve to force the presser roll 23 yieldably toward the adhesive-applying roller 15.

35 The adhesive-applying roller 15 and the presser roll 23 are provided respectively with gears 28 and 29 of equal diameter and the gear 28 is driven by a larger gear 30 rotatably mounted upon a stud shaft 31. The gear 30 has secured to it a ratchet 32 which is engaged by a spring-actuated pawl 33 which is carried by a gear 34 and the gear 34 is operated by a toothed sector 35, the hub 36 of which is secured to a shaft 37 journalled in suitable bosses on the cover 5 of the reservoir and provided with a lever 38 which may be actuated by the finger of the operator. An arm 39 extending from the shaft 37 is connected by a helical spring 40 to a suitable anchorage upon the cover 5 of the reservoir and serves normally to return the sector to the position illustrated in Fig. 1.

45 In the operation of the device the raising of the lever 38 by the finger of the operator rotates the sector 35 in a counterclockwise direction thereby rotating the gear 30 and causing its pawl to engage and rotate the gear 30 which is attached to the ratchet. The gear 30 transmits rotation to the gears 28 and 29 thereby simultaneously rotating

the adhesive-applying rollers and the presser roller which co-operates with it so that when the lower end of the label is engaged in the bite of the adhesive-applying roller and co-operating presser roller it will be advanced 70 and a film of adhesive simultaneously applied to the under surface thereof.

75 The strippers 22 prevent the label from being carried into the reservoir by the adhesive-applying roller and also direct it along the inclined surface 4 of the label supporting and guiding means. Thus the label may be forced along the label-supporting means, pasted and delivered to the article to which it is to be applied.

80 Suitable means are also provided for pressing the labels smoothly upon the article. The preferred means which is illustrated herein comprises a squeegee roller 41 of rubber or other suitable material, the shaft of which is journalled in bosses 42 extending beyond the inclined surface 4 of the front wall 3 of the reservoir. The gear 43 desirably is secured to the shaft of the squeegee roller and is driven through an idle gear 44 which is mounted in a stud shaft projecting inwardly from plates 44^x which are secured to the base 1. The gears 43 and 44 preferably are of the same diameter as the gears 28 and 29 so that the squeegee roller is 90 rotated at the same speed as the adhesive-applying roller 15 and the presser roller 25 but it will be understood that any desired ratio of gearing may be employed.

95 By virtue of this construction the entire 100 train of gears are operated in unison to feed labels from the label support, apply adhesive thereto, and also to affix the label upon the article to which it is to be applied.

105 The presser roller 25 has a series of ribs 45 presenting narrow edges to engage the upper surface of the label. Such narrow edges prevent the accidental transmission of a sufficient amount of adhesive to the presser roller to interfere with the proper operation 110 of the device.

115 The label support 16 desirably is provided with extensions 46 which project into the grooves of the adhesive-applying roll and serve to guide the label more effectively into the bite of the adhesive-applying and presser rollers.

120 An edge guide 47 desirably is secured to one of the edges of the label-supporting table 16 so that the edges of the label or pile of labels upon said support may be pressed against the guide and the labels thereby conveniently directed by the operator properly into the bite of the adhesive-applying and presser rollers.

125 In the operation of the machine a label, or preferably a pile of labels which have been arranged to have their lower ends successively exposed, are held placed upon the label support 16 with their edges against the 130

guide 47 and are lowered until the lowermost label is engaged in the bite of the adhesive-applying roller and the co-operating presser roller. The squeegee roller is then placed upon the article 48 to which the label is to be applied and the finger lever 38 raised by the operator until the lowermost label is advanced by the rotation of the adhesive-applying and presser rollers 15 and 23 over the surfaces 4 into engagement with the article. Thereupon the whole machine is moved along the article simultaneously with the further raising of the finger lever 38 so that the rotating squeegee roller will press the label down smoothly upon the article. Thus labels may be rapidly and smoothly applied to the articles, the movement of the machine being controlled mainly by the engagement of the positively driven squeegee roll with the article to which the label is being applied.

It will be understood that the embodiment of the invention disclosed herein is of an illustrative character and that various changes in form, construction and arrangement of parts may be made within the spirit and scope of the following claims.

Having thus described the invention, what is claimed as new and desired to be secured by Letters Patent, is:

1. A bodily movable hand-operable labelling machine comprising a handle, label-supporting means, an adhesive-containing reservoir, and manually-operable means having a lever adapted to be actuated by the hand which grasps the handle for advancing a label from said label-supporting means and simultaneously applying adhesive to one face of the label during, but independently of, the bodily movement of the labelling machine.

2. A bodily movable hand-operable labelling machine comprising a handle, label-supporting means, an adhesive-containing reservoir, manually-operable means, having a lever adapted to be actuated by the hand which grasps the handle for advancing the label from said label-supporting means and simultaneously applying adhesive to one face of the label during, but independently of, the bodily movement of the labelling machine, and adjustable means for regulating the amount of adhesive applied to the label.

3. A bodily movable hand-operable labelling machine comprising a handle, label-supporting means, an adhesive-containing reservoir, manually-operable means, having a lever adapted to be actuated by the hand which grasps the handle for advancing the label from said label-supporting means and simultaneously applying adhesive to one face of the label during, but independently of, the bodily movement of the labelling machine, means operable by bodily movement of said machine to press the adhesive-coated

label smoothly upon the article to which it is applied.

4. A bodily movable hand-operable labelling machine comprising label-supporting means, an adhesive-containing reservoir, manually-operable means for advancing the label from said label-supporting means and simultaneously applying adhesive to one face of the label during, but independently of, the bodily movement of the labelling machine, and a squeegee roller positioned to engage the label as it is advanced from the adhesive-applying means, and operable conjointly by the manually operable label advancing means and by a bodily movement of said machine to press the adhesive-coated label smoothly upon the article to which it is applied.

5. A bodily movable hand-operable labelling machine comprising a reservoir for an adhesive, a handle, label-supporting means having a slot communicating with said reservoir, manually-operable means for advancing a label from said supporting means, including an adhesive-applying roller partially submerged in the adhesive and having its peripheral surface extending through said slot, and gearing having an operating handle for rotating said adhesive-applying roller independently of the bodily movement of the labelling machine.

6. A bodily movable hand-operable labelling machine comprising a reservoir for an adhesive, a handle, label-supporting means having a slot communicating with said reservoir, manually-operable means for advancing a label from said supporting means, including an adhesive-applying roller partially submerged in the adhesive and having its peripheral surface extending through said slot, gearing having an operating handle for rotating said adhesive-applying roller independently of the bodily movement of the labelling machine, a doctor blade co-operating with said adhesive-applying roller, and means for adjusting said blade relatively thereto to regulate the amount of adhesive applied to the label.

7. A bodily movable hand-operable labelling machine comprising a reservoir for an adhesive, a handle, label-supporting means having a slot communicating with said reservoir, manually-operable means for advancing a label from said supporting means, including an adhesive-applying roller partially submerged in the adhesive and having its peripheral surface extending through said slot, gearing having an operating handle for rotating said adhesive-applying roller independently of the bodily movement of the labelling machine, whereby the latter will apply a coat of adhesive to the under face of said label, and a squeegee roller positioned to engage the uncoated side of the label and operable conjointly by said manually oper-

able means and by a bodily movement of the machine to affix the label to the article to which it is applied.

8. A bodily movable hand-operable labeling machine comprising a reservoir for an adhesive, a handle, a label-supporting means having a slot communicating with said reservoir, manually-operable means for advancing a label from said supporting means, including an adhesive-applying roller partially submerged in the adhesive and having its peripheral surface extending through said slot, means for rotating said adhesive-applying roller independently of the bodily movement of the labelling machine, whereby the latter will apply a coat of adhesive to the under face of said label, a squeegee roller positioned to engage the uncoated side of the label and operate by a bodily movement of the machine to affix the label to the article to which it is applied, and means for simultaneously rotating said adhesive-applying roller and said squeegee roller.

9. A bodily movable hand-operable labeling machine comprising a reservoir for an adhesive, a handle, label-supporting means presenting a slot, communicating with said reservoir, an adhesive-applying roller partially submerged in said adhesive and having its peripheral surface extending through said slot, a yieldable roller co-operating with said adhesive-applying roller, a train of gears for rotating said rollers, and manually-operable means for actuating said train of gears independently of the bodily movement of the labelling machine.

10. A hand-operable labeling machine comprising a reservoir for an adhesive, a handle, label-supporting means presenting a slot, communicating with said reservoir, an adhesive-applying roller partially submerged in said adhesive and having its peripheral surface extending through said slot, a yieldable roller co-operating with said adhesive-applying roller, a train of gears for rotating said rollers including a ratchet-actuated gear, and a spring controlled finger lever having a toothed sector engaging said ratchet-actuating gear.

11. A hand-operable labeling machine comprising a reservoir for an adhesive, a handle, label-supporting means presenting a slot, communicating with said reservoir, an adhesive-applying roller partially submerged in said adhesive and having its peripheral surface extending through said slot, a yieldable roller co-operating with said adhesive-applying roller, a squeegee roller located in proximity to the end of and co-operating with the label-supporting means, and a train of gears for rotating all of said rollers including a ratchet-actuated gear and a spring controlled finger lever having a toothed sector engaging said ratchet-actuating gear.

12. A hand-operable labeling machine comprising a base member chambered to provide a reservoir for an adhesive and having an end wall presenting a label supporting and guiding surface disposed in inclined relation to said base, a handle member mounted on said base, a label support adjustably mounted upon said handle, presenting a surface lying in the same plane as the label supporting and guiding surface of said end wall with its front end in proximity to the front wall of said reservoir to provide a slot therebetween, an adhesive-applying roller journaled in said base having its periphery partially immersed in the adhesive and projecting through said slot, and a yieldable roller co-operating with said adhesive-applying roller and manually-operable means for rotating said rollers to advance the label from said label support and to supply a coat of adhesive to the lower face thereof.

13. A hand-operable labeling machine comprising a base member chambered to provide a reservoir for an adhesive and having an end wall presenting a label supporting and guiding surface disposed in inclined relation to said base, a handle member mounted on said base, a label support adjustably mounted upon said handle, presenting a surface lying in the same plane as the label supporting and guiding surface of said end wall with its front end in proximity to the front wall of said reservoir to provide a slot therebetween, an adhesive-applying roller journaled in said base having its periphery partially immersed in the adhesive and projecting through said slot, a yieldable roller co-operating with said adhesive-applying roller and manually-operable means for rotating said rollers to advance the label from said label support and to apply a coat of adhesive to the lower face thereof, and a doctor blade co-operating with the adhesive applying roller and adjustably clamped between said adjustable label support and said handle member.

14. A hand-operable labeling machine comprising a base member chambered to provide a reservoir for an adhesive and having an end wall presenting a label supporting and guiding surface disposed in inclined relation to said base, a handle member mounted on said base, a label support adjustably mounted upon said handle, presenting a surface lying in the same plane as the label supporting and guiding surface of said end wall with its front end in proximity to the front wall of said reservoir to provide a slot therebetween, an adhesive-applying roller journaled in said base having its periphery partially immersed in the adhesive and projecting through said slot, and a yieldable roller co-operating with said adhesive-applying roller, a squeegee roller

mounted on said frame in proximity to the inclined label supporting and guiding surface of said end wall, and manually-operable means for rotating all of said rollers.

- 5 15. A hand-operable labeling machine comprising a base member chambered to provide a reservoir for an adhesive, an adhesive-applying roller journaled in said base having peripheral circular grooves and
10 located in proximity to one end wall of said reservoir, strippers extending from said end wall into said grooves and presenting contin-

uations of an inclined label-guiding surface of said end wall, a roller having ribs presenting narrow edges co-operating with said adhesive-applying roller, and manually-operable means for rotating said co-operating rollers to advance a label from said label-supporting means and coat one face thereof with adhesive.

20 In testimony whereof, I have signed my name to this specification.

CARL E. PUTNAM. [L. s.]
